(57) **CLAIM**

The ornamental design for a cap, as shown and described.

DESCRIPTION

FIG. 1 is a top, front perspective view of a cap showing our new design;

FIG. 2 is a second top, front perspective view thereof;

FIG. 3 is a top plan view thereof;

FIG. 4 is a bottom, front perspective view thereof;

FIG. 5 is a bottom plan view thereof;

FIG. 6 is a front elevation view thereof, with the rear elevation, left side, and right side views being identical thereto; and,

FIG. 7 is a top perspective cross-sectional view taken in the direction of line 7-7 shown in FIG. 3.

The broken lines in the drawings form no part of the claimed design.

1 Claim, 7 Drawing Sheets
